W. M. ROHN.

RAZOR HONING AND STROPPING DEVICE,
APPLICATION FILED MAR. 22, 1916.

1,209,500.

Patented Dec. 19, 1916

UNITED STATES PATENT OFFICE.

WILLIAM M. ROHN, OF DETROIT, MICHIGAN.

RAZOR HONING AND STROPPING DEVICE.

1,209,500.

Specification of Letters Patent. Patented Dec. 19, 1916.

Application filed March 22, 1916. Serial No. 35,827.

To all whom it may concern.

Be it known that I, WILLIAM M. ROHN, a citizen of the United States, residing at Detroit, in the county of Wayne and State of Michigan, have invented certain new and useful Improvements in Razor Honing and Stropping Devices, of which the following is a specification, reference being had therein to the accompanying drawing.

10 This invention relates to improvements in razor stropping and honing devices, it being more especially adapted for use in connection with safety razor blades, one object of the invention being the provision of a device 15 of this character which is provided with a blade carrying and coöperative shifting means for placing the blade in proper co-operation with the honing and stropping member, as the same is reciprocated.

20 A further object of this invention is the provision of a stropping and honing device which is simple, durable and inexpensive in construction and thoroughly efficient and practical in use.

25 With the foregoing and other objects in view, and which will appear as the description proceeds, this invention resides in the novel arrangement and combination of parts as herein set forth, it being possible, however, to change the details of construction, which are only limited by what is claimed.

In the accompanying drawings;—Figure 1 is a top plan view, the strop being broken away. Fig. 2 is a side elevation thereof. Fig. 3 is a section taken on line 3—3 of Fig. 2. Fig. 4 is a top plan view of the stropping and honing member, a portion being broken away to show the resilient connection between the ends. Fig. 5 is an enlarged detail 40 sectional view of the honing portion of the strop. Fig. 6 is a plan view of the blade carrier blank.

Referring to the drawings, the numeral 10 designates the two side plates, which are 45 connected together by means of the spacing plates 11 and thus constitute a supporting structure or frame for the device.

The side plates are each provided with the two parallel slots 12 and 13, while 50 mounted for sliding movement adjacent the outer face of such plates are the depending flat ends 13' of the carriage 14 having the connecting member 15 to which is detachably connected the manipulating handle 16. 55 Journaled between the flat ends and extending between the plates 10 and through the

lower slots 13 is a shaft 14 which is provided with the corrugated surface 17 and has fast thereto the gear or pinion 18. Also mounted in the carriage above the last mentioned 60 shaft is the blade carrier or clamp 19 which with its journaling pintles 20 is made from a single sheet of metal, as illustrated in Fig. 6, such pintles being extended through the upper slots 12, and one thereof having secured rigidly thereto the pinion 21 which is 65 in mesh at all times with the pinion 18.

The razor blade 21' is adapted to be removably fitted in the clamp 19 so that the edge thereof will always be projected in the 70 opposite direction to the movement of the carriage. In order to insure this, a metal strip 22 is provided with openings 23 at the terminals thereof for receiving the supporting springs 24 which in turn are connected 75 to the upper edges of the retaining plates 11. In this manner, the strip is supported resiliently so that the relatively soft friction surface or strap 25 connected to the upper surface thereof and preferably made of 80 leather will engage the corrugated portion of the lower shaft and due to the coöperation of the springs, such surface will rotate the shaft at the initial movement of the carriage so as to dispose the blade away 85 from the direction of travel of the carriage and upon the honing and stropping member 26, the continued movement of the carriage and the coöperation between the corrugated shaft and the leather strap maintaining a 90 steady pressure upon the blade relatively to the stropping and honing member. This stropping and honing member is preferably made of a strip of flexible material, leather or the like, and is adapted to be disposed 95 around the rollers 28 mounted upon the rods 29 and between the corrugated shaft and the blade carrying member of the carriage, the ends of the same being each provided with the metal connections or pieces 30 which in turn are provided with the eyes 31 for the reception of the spring 32 which thus holds the flexible member at the proper tautness at all times.

The button or handle 33 is connected so 105 that the flexible member constituting the strop or hone may be moved longitudinally to present the stropping surface 34 or the honing surface 35 to receive the blade during the reciprocation of the carriage.

The honing surface is preferably made by producing a great number of punctures 36 in

the surface of the strop and filling such punctures with an abrasive material 37 such as carborundum which may be baked therein and produce a honing surface which will become harder with wear and thus make of that portion of the strop an efficient hone for the blade.

What I claim as new is:—

1. In a device of the character described, 10 a frame, a carriage mounted therein for reciprocation, a shaft journaled in the carriage, a blade carrying clamp also journaled in the carriage, coöperative transmission means between the clamp and the shaft, a 15 honing and stropping member carried by the frame and interposed between the shaft and the clamp, and means disposed in the path of the shaft for coöperating therewith to rotate the same at the initial movement of the 20 carriage and for maintaining the clamp with its free edge toward and upon the stropping and honing member.

2. In a device of the character described, 25 a frame having two side plates provided each with two longitudinal parallel slots therethrough, a carriage having two side members fitting astride of said plates for reciprocation, a shaft journaled in said side members in the carriage and projected trans- 30 versely in the frame through the lower slots thereof, a blade carrier journaled in said carriage and spaced from the shaft, transmission means between the shaft and the blade carrier, whereby the blade carrier is rotated 35 through the shaft, resiliently supported friction means mounted within the frame and in contact with the shaft, whereby as the carriage is reciprocated, said shaft is rotated, and a razor stropping and honing member 40 mounted in the frame, between the shaft and blade carrier.

3. In a device of the character described, 45 a frame having two side plates provided each with two longitudinal parallel slots therethrough, a carriage having two side members fitting astride of said plates for reciprocation, a shaft journaled in said side members in the carriage and projected trans- 50 versely in the frame through the lower slots thereof, a blade carrier journaled in said carriage and spaced from the shaft, transmission means between the shaft and the blade carrier, whereby the blade carrier is rotated through the shaft, resiliently supported friction means mounted within the 55 frame and in contact with the shaft, whereby as the carriage is reciprocated, said shaft is rotated, a flexible strop passed between the shaft and blade carrier and mounted within the frame, and a spring connecting the terminals of said strop to impart a resilient 60 tautness to the strop.

4. In a device of the character described, a frame composed of two side plates and two transverse retaining plates, a carriage 65 mounted for movement upon the side plates, a shaft carried by the carriage, a blade carrier also carried by the carriage and operably connected to the shaft, a resiliently supported member connected to the retaining plates and disposed longitudinally within the frame and for contact with the shaft whereby at the initial movement of the carriage in either direction, the shaft is rotated to project the blade carrier in an opposite 75 direction to the movement of the carriage.

5. In a device of the character described, a frame composed of two side plates and two transverse retaining plates, a carriage mounted for movement upon the side plates, 80 a shaft carried by the carriage, a blade carrier also carried by the carriage and operably connected to the shaft, a resiliently supported member connected to the retaining plates and disposed longitudinally within the frame and for contact with the shaft whereby at the initial movement of the carriage in either direction, the shaft is rotated to project the blade carrier in an opposite 85 direction to the movement of the carriage, and a flexible honing and stropping member disposed around the retaining plates and between the shaft and blade carrier for receiving the cutting edge of the blade during the reciprocation of the carriage.

6. In a device of the character described, 90 a frame, a carriage mounted thereon for reciprocation, an oscillatory blade carrier mounted in the carriage, and coöperative means for shifting the blade carrier respectively mounted in the carriage and supported by the frame, the portion thereof supported by the frame being held resiliently so as to exert a resilient tension upon the portion mounted in the carriage.

7. In a device of the character described, 95 a frame composed of two side plates, and two transverse retaining plates, a plurality of rollers journaled between the side plates beyond the retaining plates, a flexible honing and stropping member passed around the rollers above and below the transverse plates, means for resiliently connecting the ends of the same together, means for imparting longitudinal movement to the member to dispose the stropping or honing portions thereof in active position, and a blade manipulating carriage mounted for sliding movement in the frame and in co-active relation with the honing and stropping member.

In testimony whereof I affix my signature.

WILLIAM M. ROHN.
